COMBINED SEARCHLIGHT AND REAR VIEW MIRROR

Douglas R. Cleminshaw, 916 Lancaster Ave., Syracuse, N.Y.; Donald Lee Du Sell, 114 Midwood, Liverpool, N.Y.; and Arthur J. Pulos, 201 Churchill Lane, Fayetteville, N.Y.

Filed June 4, 1959, Ser. No. 56,213

Term of patent 14 years

(Cl. D14—6)

FIG. 1

FIG. 2

FIG. 3

Figure 1 is a top plan view of a combined searchlight and rear view mirror showing our new design;

Figure 2 is a front perspective view thereof; and

Figure 3 is a rear perspective view thereof, with the searchlight element in horizontal position.

The side not shown is substantially the same in appearance as the side shown.

We claim:

The ornamental design for a combined searchlight and rear view mirror, substantially as shown and described.
